Application March 1, 1955, Serial No. 491,406

2 Claims. (Cl. 260—683.6)

This invention relates to a process for improving the quality of light catalytic naphthas. The invention is directed to a specific hydrogenation treatment applicable to a particular selected fraction of a catalytically cracked naphtha. The invention provides a means for greatly improving the Motor method octane rating of such catalytic naphtha fractions.

The invention involves fractionation of a catalytically cracked naphtha into at least two fractions, one of which constitutes the portion of the naphtha boiling in the range of about 65° to 115° F. Hydrogenation of this particular fraction provides substantial and unexpected advantages as regards the quality of the resultant hydrogenation products. The invention is based on the discovery that the fraction of a catalytic naphtha boiling in the range of about 65° to 115° F.; that is, the pentene fraction, is particularly susceptible to improvement in anti-knock quality under specific hydrogenation conditions. It is known that hydrogenation of cracked naphthas ordinarily results in degradation in the anti-knock quality of the naphtha as evidenced by a substantial loss in the Research octane rating and very little, if any, improvements in the Motor method octane rating. Unexpectedly, however, by hydrogenating the fraction of a catalytic naphtha boiling in the range of 65° to 115° F., it is possible to secure great improvements in the Motor method octane rating of this particular fraction accompanied by little, if any, loss in the Research method octane rating. It is the basic concept of this invention therefore, to provide a hydrogenation treatment for upgrading the anti-knock quality of this specific fraction of a catalytic naphtha which is separated from the naphtha for this treatment.

In a specific embodiment of the present invention, a catalytic naphtha is divided into the pentene fraction and a heavier naphtha fraction and both of these fractions are subjected to different and specific hydrogenation conditions. By this means it is possible to upgrade the total catalytic naphtha by a hydrogenation treatment to obtain results which cannot be achieved by hydrogenation of the total naphtha.

The invention will be fully identified in the description which follows, and with reference to the accompanying drawing which diagrammatically illustrates a flow plan of a specific and preferred embodiment of the invention.

One of the most important requirements of a high quality gasoline at the present time relates to the anti-knock rating of the gasoline. The importance of gasolines of high anti-knock rating has been made more and critical by the trend toward engines of higher compression ratio. At the present time the compression ratio of current automobile engines has been increased to values above 6.5, ranging upwardly to as high as 12. Engines having such high compression ratios require use of high anti-knock gasolines. The more extended use of automatic transmissions has also aggravated the prob-

2

lem of satisfying the octane requirements of current automotive engines. In the past, octane ratings of gasolines have primarily been determined by the so-called Research method, which can be determined by ASTM test, designated D908-47T. While this is an important and valuable anti-knock rating test, it has become appreciated that the Research octane rating of a gasoline as determined by this method correlates poorly with actual road performance of a gasoline. This is true in part since the Research octane number is determined in a test procedure at which the engine is operated at conditions of constant speed and constant load. As opposed to this, the actual knocking tendency of a fuel in road performance is greatest during maximum load. It is therefore appreciated at this time that the Research octane number rating of a gasoline is not a complete indication of the value of a gasoline in satisfying an engine under road conditions.

As a result, other methods of determining octane ratings are commonly employed. One such method is the so-called Motor method test, designated by ASTM test Method D357-47. It has been found that the Motor method octane determination correlates with the road performance of a gasoline somewhat better than the Research octane rating.

In view of these basic factors, production of present day-high quality gasolines must be carried out with reference to both the Research and Motor method octane octane rating. The over-all octane rating of the fuel is some function of both of these octane rating methods and can be approximated by averaging the Research and Motor method ratings.

It is the principal object of this invention to provide a refining process particularly adapted for improving the Motor method octane rating of naphthas. This invention therefore provides a valuable tool for providing higher quality gasolines in a manner heretofore unobtainable.

The nature and benefits of this invention can be appreciated by reference to Table I, showing data obtained by conduct of two types of hydrogenation applied to selected fractions of a light catalytic naphtha as compared to this same treatment of the total light naphtha. In one of the hydrogenation operations employed, conditions were adjusted to secure essentially complete saturation of olefinic hydrocarbons present in the feed stock. This was achieved by treating the naphtha feed stock at a temperature of 700° F., a pressure of 200 p. s. i. g. at a throughput of 1.7 v./v./hr., in the presence of 1500 S. C. F. B. of hydrogen in contact with a cobalt molybdate on alumina catalyst. Under these hydrogenation conditions, approximately 98% of the olefins present in the feed were saturated. In the other hydrogenation operation employed, using the same catalyst at the same temperature and with the same amount of hydrogen, and at throughputs of about 1.5 to 2 v./v./hr., pressure was maintained at the lower figure of 50 p. s. i. g., so as to cause partial saturation of the olefins present in the feed. Under these conditions, approximately 43% of the olefins were hydrogenated to saturation.

In the conduct of these experiments, three types of naphtha feed stock were employed. The first of these constituted the whole of a light catalytic naphtha boiling in the range of about 65° F. to 363° F. A second fraction constituted only that portion of this naphtha boiling in the range of about 115° to 150° F. Finally, a third hydrogenation feed stock constituted only the pentene fraction of the light catalytic naphtha boiling in the range of about 65° to 115° F. The results of applying these hydrogenation treatments to these feed stocks under the conditions specified are shown in Table I.

TABLE I
Hydrogenation of light catalytic naphtha

Olefin Saturation, Percent.....	Complete Saturation			Partial Saturation		
	98			43		
	C ₅	115/150	C ₅ /363° FEP	C ₅	115/150	C ₅ /363° FEP
Vol. Percent on Total Naphtha.....	22	17	100	22	17	100
Octane Change (3 cc. TEL):						
Motor.....	+14.0	+6.5	+4.5	+7.0	+2.5	+2.5
Research.....	-1.5	-7.0	-7.0	+1.0	-1.5	-2.0
Net octane change.....	+12.5	-0.5	-2.5	+8.0	+1.0	+0.5
Final Motor Octane (3 cc. TEL).....	100	92.5	88.5	93	88.5	86.5
Hydrogen Consumption, S. C. F./B.....	650	630	520	300	300	220

Referring to Table I, it will be observed that hydrogenation of the total naphtha conducted to secure complete saturation of olefins present, resulted in a substantial drop in the Research octane rating of the gasoline. This hydrogenation treatment resulted in a loss of 7 Research octane numbers. The operation caused a small improvement in the Motor octane rating of the gasoline amounting to 4.5 octane units. However, it is apparent that the substantial loss in Research octane number would ordinarily far offset any value obtained by appreciation of the small gain in Motor octane number. When treating the total naphtha under the milder hydrogenation conditions, causing partial saturation of olefins present, a smaller loss in Research octane resulted, although in this case the Motor octane rating of the hydrogenated naphtha improved but little. Again, therefore, application of this hydrogenation treatment to the total naphtha is shown to be of little or no value so far as improving the overall octane quality of the gasoline.

As opposed to this, the data of Table I shows the substantial and unexpected improvement in the anti-knock quality obtainable when applying these same hydrogenation conditions only to the pentene fraction of the naphtha. In particular, the data show that in the complete saturation hydrogenation treatment applied to the pentene fraction of the naphtha, it was possible to increase the Motor method octane rating of this fraction by 14 units. Concomitantly, there was little change in the Research rating of the pentene fraction amounting only to a decrease of 1.5 units which was substantially less than that resulting from treating the total naphtha under the same hydrogenation conditions. The partial saturation hydrogenation treatment, when applied to only the pentene fraction of the naphtha again showed substantial advantages over treatment of the total naphtha. Thus, the partial saturation treatment of the pentene fraction resulted in a gain of 7 octane units by the Motor method and of one octane unit by the Research method. The data of Table I therefore, shows the substantial and unexpected advantages of segregating the pentene fraction from a catalytic naphtha and applying a hydrogenation treatment to this specific fraction. By so doing, it becomes possible to greatly improve the Motor octane rating of this specific fraction while avoiding the degradation in Research octane rating otherwise resulting from hydrogenation of the total catalytic naphtha.

With reference to the hydrogenation of the intermediate naphtha fraction boiling within the range of 115° to 150° F., the data of Table I again shows that this fraction can not be appreciably upgraded in octane characteristics. Thus, because of loss in the Research octane rating, hydrogenation of this fraction at either partial or complete saturation conditions provides substantially no better result than treatment of the total naphtha. This data therefore establishes that hydrogenation of the pentene fraction of a catalytic naphtha by itself provides significant and unexpected improvement in anti-knock char-

acteristics not obtainable by hydrogenating the total naphtha or narrow fractions of the naphtha other than the pentene fraction.

As formerly stated, the over-all octane rating of a gasoline is best indicated by a consideration of both the Research and Motor method octane rating. To weigh in this consideration "net octane change" is indicated in Table I which is simply the sum of the Research and Motor method octane changes resulting from hydrogenation of the different stocks. The unexpected and substantial advantage of hydrogenating the pentene fraction alone is particularly indicated by the "net octane change" data.

The remarkable increase in the Motor octane rating of the pentene fraction obtainable by hydrogenation is primarily due to the increased lead susceptibility of the hydrogenated pentenes. Data establishing this are shown in Table II.

TABLE II

Motor Octane Number	Feed	Saturated Product	Δ
Leaded (3 MI. TEL).....	86.0	99.9	+13.9
Clear.....	81.2	82.1	+0.9
Δ Due to TEL.....	+4.8	+17.8	

These data show that while the clear octane number of the hydrogenated pentene fraction is but little better than that of the unhydrogenated fraction, remarkably, the leaded Motor octane number attributable to the presence of tetra-ethyl-lead is increased by 17.8 octane units.

An important feature of this invention is the manner in which hydrogen is conserved while achieving improvement in anti-knock quality. A catalytic naphtha contains a substantial amount of olefinic constituents resulting in high hydrogen consumptions when such naphthas are hydrogenated. For example, when hydrogenating a total light catalytic naphtha boiling in the range of about 65 to 363° F., a hydrogen consumption of about 500 to 600 standard cubic feet per barrel is required. From an economic viewpoint, this substantial consumption of hydrogen could not be justified for attaining the relatively insignificant change in anti-knock characteristics shown in Table I. However, by hydrogenating only the pentene fraction of a catalytic naphtha, while about the same amount of hydrogen is required per barrel of pentene feed, over-all hydrogen requirements are only a fraction of those required for treating the total naphtha. This can be appreciated by the fact that approximately a 2.0 Motor octane grain per 100 standard cubic feet of hydrogen per barrel can be achieved by treating the pentene fraction while the Motor method octane gain in treating the total naphtha with the same amount of hydrogen is only about 0.5. Consequently, in considering the hydrogenation of catalytic pentenes in accordance with this invention, as opposed to hydrogena-

tion of other fractions of a catalytic naphtha, it is apparent that this invention provides a remarkable improvement in anti-knock quality for quantity of hydrogen required.

The data of Table I, shows that partial saturation of the pentene fraction attains about half the improvement in Motor octane number which can be obtained by total saturation. These data are particularly significant in considering makeup of a refinery gasoline pool. Olefinic constituents have a more desirable octane blending factor than paraffinic constituents, and for this reason by partially saturating the pentene fraction as shown in Table I, the over-all effect in a gasoline pool is substantially that obtainable by complete saturation of the pentene fraction. For this reason it is a particular feature of this invention to partially saturate rather than to completely saturate the pentene fraction of a light catalytic naphtha so as to further conserve hydrogen consumption and to provide a pool gasoline product of substantially the octane characteristics obtainable by other processes requiring greater amounts of hydrogen. In this connection it is generally preferred to saturate about 30% to 60%, for example, about 40% of the olefins present in the pentene fraction.

While the process of this invention has a desirable effect on the sulfur content of naphthas treated in accordance with the invention, the process would not normally be used for this purpose and cannot be considered a desulfurization operation. Catalytic naphthas by their nature are generally of low sulfur content due to conversion and elimination of sulfur compounds during catalytic cracking. Consequently, catalytic naphthas ordinarily have sulfur contents in the relatively low range of about 0.02 to 0.10%. Of this sulfur content, practically all of the sulfur is contained in the higher boiling fractions of the naphtha. The pentene fraction of a catalytic naphtha separated by fractionation only contains about 0.02% of sulfur constituting less than 5% of the total sulfur in the naphtha. Hydrogenation of the pentene fraction even when conducted to secure maximum desulfurization only reduces the sulfur content to a level of about 0.0002% to 0.001%. Thus, if this desulfurized pentene fraction were to be blended back with the heavier naphtha fractions to reconstitute the total naphtha, the sulfur content of the total naphtha would only be changed by about 5%. It is apparent then that the process of this invention, while being of advantage in somewhat reducing sulfur content of a naphtha cannot be considered as constituting or replacing other desulfurization operations.

In obtaining a total catalytic naphtha of highest quality, it is desirable to particularly treat the portion of the naphtha remaining after separation of the pentene fraction. It is particularly desirable to treat the heavier fraction of the catalytic naphtha by a hydrofining operation conducted at hydrogenation conditions different from those applied to the pentene fraction. This is achieved by hydrofining the heavier fraction of catalytic naphtha boiling above 250° F. under conditions to secure a bromine number reduction of no more than about 20%. This results in primarily improving the engine cleanliness and stability characteristics of this naphtha fraction while contributing a sulfur reduction of about one-third. Such hydrofining can be carried out using a hydrogenation catalyst such as cobalt molybdate at temperatures of about 400° to 700° F., at a pressure in the range of 50 to 250 pounds per square inch, throughputs of about 1 to 20 v./v./hr., and at hydrogen consumptions less than 60 standard cubic feet per barrel.

In conducting the hydrogenation of the pentene fraction in accordance with this invention, a wide variety of hydrogenation catalysts may be employed. Preferred catalysts constitute the oxides of cobalt or molybdenum alone or in admixture and including cobalt molybdate. Preferably, these catalytic agents are supported on an adsorbent support such as alumina. It is particularly

preferred to employ cobalt molybdate as the catalyst.

The pressure employed is to be in the range of 25 to 500 pounds per square inch although it is preferred to use pressures below 200 p. s. i. g. for the hydrogenation of the pentene fraction and it is particularly desirable to employ a pressure of about 50 p. s. i. g. Throughputs of 1 to 20 v./v./hr., may be employed although the preferred range is about 5 to 10 v./v./hr. The temperature maintained during hydrogenation is about 500° to 800° F., and specifically 700° F. Contact of the pentene fraction with the catalyst under these conditions should be carried out employing a rate of hydrogen supply above about 500 standard cubic feet of hydrogen per barrel, and generally about 1500 standard cubic feet per barrel.

15 The specific hydrogenation conditions are to be selected from the foregoing limits by regard to the resulting olefin saturation and/or hydrogen consumption. In general, for olefin saturations in the range of about 30 to 100% of the olefins present in the pentene fraction, hydrogen 20 consumptions of about 200 to 700 standard cubic feet per barrel will be employed. In treating a typical catalytic pentene fraction for complete olefin saturation, a hydrogen consumption of about 650 S. C. F./B. is ordinarily required.

25 Referring now to the drawing, a specific embodiment of this invention is illustrated showing a preferred flow plan for the practice of this invention.

As illustrated, a gas oil feed stock boiling in the range of about 400° to 1100° F., for example, may be brought 30 into catalytic cracking zone 1 through line 2. Catalytic cracking of a conventional nature will be carried out in zone 1 permitting removal of cracked products through line 3 for introduction to fractionation zone 4. Light 35 gaseous products including C₄ and lighter hydrocarbons may be withdrawn from fractionation zone 4 through an overhead line 5. A fraction including the catalytic naphtha fraction boiling in the range of about 50 to 400° F., may be removed through line 6. Higher boiling cracked products will be recovered from the fractionation 40 zone through lower withdrawal lines 7 and 8, etc.

The catalytic naphtha fraction may be passed to a secondary fractionation system 9, which may be operated to permit removal of residual amounts of C₄ and lighter constituents through overhead line 10. In accordance 45 with this invention, a sidestream is taken from fractionator 9 through line 11 constituting the pentene fraction boiling in the range of about 65° to 115° F. Preferably, a higher boiling fraction, boiling in the range of about 115° to 250° F. is withdrawn as a sidestream through line 22. Finally, a fraction boiling in the range of about 250° to 50 400° F., will be removed as a bottoms product through line 12.

The pentene fraction of line 11 is then passed to hydrogenation zone 14. In zone 14 the pentene fraction is 55 subjected to hydrogenation under the conditions identified hereinbefore to achieve an olefin saturation which is preferably about 40% or greater. The hydrogenated product may then be passed through line 15 to zone 23 for caustic or water washing although this is an optional 60 step. Thereafter, the treated pentene fraction is passed to storage zone 17 through line 16 for blending with other gasoline blending stocks.

In the preferred conduct of this invention, the naphtha fraction of line 22 is passed directly to storage zone 17. 65 This fraction requires no treatment except optional treatment for sulfur removal. If desired, however, the naphtha of line 22 may be combined with the naphtha of line 12 for treatment in hydrofining zone 18. In all cases, the heavy naphtha fraction of line 12 is subjected to the hydrofining conditions identified hereinbefore. The hydrogenated product from zone 18 is then passed into the storage zone 17 through line 20. The resultant blend of the products of lines 16, 22, and 20 constitutes a desirable high quality gasoline. It is apparent of course 70 75

that other gasoline blending stocks may also be mixed with these constituents as desirable in conventional refinery practice.

As described, therefore, the present invention relates to the upgrading of naphthas derived from a catalytic cracking process. The invention particularly concerns the treatment of specific, selected fractions of a catalytic naphtha under specific hydrogenation conditions. The basic feature of the invention is the treatment of the pentene fraction of a catalytic naphtha boiling in the range of 65° F. to 115° F. Such a fraction typically constitutes about 60% of unsaturated, olefinic compounds and 40% of saturated paraffins. More particularly, a typical pentene fraction of catalytic naphtha will constitute the following general composition:

	Percent
Branched olefins	36
Normal olefins	23
Cyclic olefins	1
Isoparaffins	38
Normal paraffins	2

The specific proportions of these constituents will of course vary somewhat in accordance with variations in the conditions of catalytic cracking and the feed stock employed. Pentene fractions adaptable to treatment by the present invention may, however, be characterized as constituting at least about 50% unsaturated hydrocarbons.

What is claimed is:

1. A process for upgrading a catalytic naphtha which comprises the steps of fractionating the naphtha to segregate a first fraction boiling below about 65° F.; a sec-

ond fraction comprising pentenes free of C₆ hydrocarbons and boiling in the range of about 65° F. to 115° F.; a third fraction boiling in the range of about 115° F. to 250° F.; a fourth fraction boiling above about 250° F.; 5 hydrogenating the second fraction to secure an olefin saturation in the range of 30% to 100% by contact with hydrogen in the presence of a hydrogenation catalyst selected from the group consisting of cobalt oxide, molybdenum oxide and cobalt molybdate supported on an adsorbent carrier at a temperature in the range of about 500° to 800° F., a pressure in the range of about 25 to 500 p. s. i., at a throughput in the range of about 1 to 20 v./v./hr., with a minimum of 500 S. C. F. of hydrogen/bbl.; hydrogenating the fourth fraction to secure a 10 maximum bromine reduction of 20% by contacting it with hydrogen in the presence of a cobalt molybdate catalyst at a temperature in the range of 400° to 700° F., a pressure in the range of 30 to 250 p. s. i., at a throughput in the range of 1 to 20 v./v./hr., with a maximum hydrogen consumption of less than about 60 S. C. F./bbl. and blending the third fraction with the treated 15 second and fourth fractions to provide a naphtha product.

2. The process of claim 1 in which an olefin saturation of about 30% to 60% is obtained.
